SOUND RECORDING

Burton F. Miller, Hollywood, Calif., assignor to
 United Research Corporation, Long Island
 City, N. Y., a corporation of Delaware

Application July 5, 1935, Serial No. 29,931

2 Claims. (Cl. 179—100.3)

This invention relates to sound translating devices and particularly to improvements in light valves for use in recording sound by the variable area method upon a photographic medium.

5 The invention is particularly adapted to be used in recording sounds to be later reproduced in synchronism with motion pictures.

In this type of light valve a narrow slit having a width in the order of about one-half mil is provided through which a beam of light is projected onto the sensitized surface of a uniformly moving film. A vibratory current carrying conductor is placed in an angular position over the slit so as to allow about one-half of the 15 length of the slit to be exposed to the beam of light when no current is flowing through the conductor. A strong magnetic field having its flux at right angles to the plane of the conductor is provided by a magnetic frame having its poles placed closely adjacent the slit and conductor. When an alternating speech current is passed through the conductor the interaction between the magnetic field and the magnetic force produced by the current flowing through the conductor causes the conductor to vibrate back and forth in accordance with the amplitude and frequency of the current thus changing the length of the exposed portion of the slit to the beam of light.

30 In my co-pending application Serial No. 28,109, filed June 24, 1935, for Sound recording, I have disclosed and claimed a light valve having a single electrical conductor vibratile at the frequencies to be recorded which is placed 35 across an aperture for producing a noiseless sound track of the double hump type. While it contains claims generic to the arrangement disclosed in detail here, that case specifically discloses the use of a triangular aperture in the 40 path of the recording light beam, the single conductor moving parallel to the base of the triangular aperture.

An object of the present invention is to adapt the apparatus of my co-pending application referred to above to the recording of a noiseless sound track of the single hump type.

This is accomplished by modulating the recording light beam by means of a single conductor moving angularly with respect to a rectangular 50 slit.

The invention further relates to improvements in the mounting for the single string conductor.

This invention is illustrated in the accompanying drawings in which:

55 Fig. 1 is a transverse section of a light valve

taken along the line 1—1 of Fig. 2 and diagrammatically showing the arrangement of an optical system associated therewith.

Fig. 2 is a sectional view taken along the line 2—2 of Fig. 1. 5

Fig. 3 is a longitudinal section taken along the line 3—3 of Fig. 2.

Fig. 4 is an enlarged fragmentary view of the light slit and its associated vibrating conductor.

Fig. 5 shows the length of film having a variable area sound track thereon, as produced by 10 the light valve.

Fig. 6 is a schematic view showing the application of a noise reduction circuit.

Figs. 7 and 8 are diagrammatic views showing 15 the method of adjusting the biasing of the vibratile conductor.

Fig. 9 is an enlarged fragmentary view of a positive film having a variable area sound track resulting from the use of the noise reduction circuit shown in Fig. 6. 20

Fig. 10 is an enlarged fragmentary view showing a sound track produced by the noise reduction circuit in Fig. 6.

Referring now to Fig. 1, an exciter lamp 1 of 25 constant intensity projects a beam of light 2 through a pair of condenser lenses 3, from whence it is focused to a point F within the light valve generally indicated at 4. Here the beam of light 2 is changed into a narrow slit of light 30 of varying length. An objective lens 5 focuses the slit of light upon the sensitized surface of a continuously moving film 6.

Referring now to Figs. 1, 2, and 3, the light valve 4 comprises a magnetic frame made up of 35 a base plate 7 of magnetic material, which is secured at its outer ends to the depending legs 8 and 9 of an upper magnetic frame 10 by means of screws 11. The upper frame 10 has a hollow core 12 provided thereon, which acts as one pole 40 of the magnet. A magnetic coil 13 receives a substantially constant direct current to produce a magnetic flux between the core 12 and a pole piece 14, which is secured to the lower base plate 7 in alignment with the core 12, as shown in Fig. 45 1. The pole piece 14 is provided with an aperture 15 to allow the beam of light to be projected therethrough. The ends of the core 12 and the pole piece 14 are placed closely adjacent each other so as to produce as strong a magnetic 50 flux as possible.

Mounted on the base plate 7 adjacent the pole piece 14 are a pair of bridges 16 and 17, having raised portions 18 and 19, upon which a vibrating conductor 20 rests. The bridges 16 and 17 are 55

formed of insulating material such as Bakelite or hard rubber. The conductor 20 is secured at one end to a windlass 21, for the purpose of adjusting the tension of the conductor 20. The other end of conductor 20 is passed around a spring pressed arm 23 and is secured to a windlass 25 similar to that of 21. The arm 23 is pivotable about a stud 24 and is urged outwardly toward the leg 8 by a torsion spring 61 thus serving to prevent undue tension from being placed upon the conductor 20. The windlasses 21 and 25 are electrically connected by means of conductors 46 and 47 to terminals 22 and 35 which, in turn, are connected through wires 56 and 57 to suitable sound recording amplifiers not shown. When a current is passed through the conductor 20, the interaction between the magnetic field set up by the conductor 20 and the magnetic field between the hollow core 12 and the pole pieces 14 and 15 will cause a movement of the conductor 20 to one side or the other depending on the direction of the current.

Referring now to Fig. 1, the beam of light 2 is focused upon a slit 34 defined by a pair of slit forming members 26 and 27 which are secured upon supporting members 28 and 29 by means of clamping plates 30 and 31. The sides of the members 26 and 27 are engaged by a pair of transversely extending plates 48 and 49, also secured by means of the clamping plates 30 and 31 to define the ends of the slit 34. Of course, it should be understood that the slit 34 may also be defined by the edges of the pole piece 14. The members 28 and 29 are secured to the base plate 7 by means of screws such as 32 and 33.

Referring now to Fig. 4, the vibrating conductor 20 is so adjusted with respect to the slit 34 formed by the members 26 and 27 that it crosses it at a slight angle, which in the present instance is slightly over one degree. Due to the fact that the natural period of vibration should preferably be above the range of audibility, it is necessary to keep the mass of the conductor 20 as small as possible. In this instance the conductor 20 is in the form of a flat ribbon about .0005" thick and about .006" wide and is constructed of Duralumin or other light material. These dimensions of course may be varied in accordance with different conditions and requirements. When no current is flowing, the conductor 20 covers approximately one-half of the area of the slit 34. When an alternating current is passed through the terminals 22 and 35, the conductor 20 is caused to move in a direction perpendicular to the magnetic flux between the hollow core 12 and the pole piece 14 so as to change the length of the exposed portion of the slit 34. The tension and angle of the conductor 20 is so adjusted that at full modulation the entire slit 34 is covered at one instant while at another instant the whole area of the slit is exposed. This exposure of the slit 34 is, of course, directly proportional to the amplitude of the current passing through the conductor.

In order to provide adjustment of the conductor 20 in relation to the slit 34, the bridges 16 and 17 have adjusting jaws 36, 37, 38 and 39 thereon. These jaws are preferably formed of a spring material and are secured at their rear ends to the bridges 16 and 17 by screws 40 and 41. The forward ends of the jaws are bent inward to engage the sides of the conductor 20 and are adjustably secured to the bridges 16 and 17 by means of adjusting screws 42 and 43. Thus, both the angle made between the conductor 20

and the slit 34 and also the initial position of the conductor 20 at no modulation may be varied.

At Fig. 5 is shown a section of a positive print of a moving picture film 44, having a variable area sound track portion 45 at one edge thereof formed by the passage of the film before the light valve 4.

Referring to Figs. 6, 7, and 8, I will now describe the application of noise reduction to the recording of sound by my improved light valve. The recording circuit (Fig. 6) comprises a microphone 50 wherein sound waves are received and are translated into electrical currents of equivalent wave form and proportionate amplitude. In circuit with the microphone 50 is an amplifier 51 and a transformer 52 which supplies an amplified audio frequency current to the vibrating conductor 20 of the light valve 4. A noise reduction amplifier 53 and rectifier 54 are shunted across the light valve circuit to provide a bias neutralizing current through the conductor 20. Biasing current is provided by a battery 61 so as to hold the conductor 20 in the position shown by the dot and dash lines 20 of Fig. 4 when no or little sound is being recorded. Thus the center of modulation as represented by the line 58 (Fig. 9) is held to the left of the center of the sound track 59 when recording low level sounds as at point L. When high level sounds are recorded, a current which increases in proportion to the increase in level of the sound is impressed upon the amplifier 53 and rectifier 54. The rectified current is fed to the conductor 20 in a direction opposite to that fed by the battery 61 to thus neutralize the biasing current produced by the battery 61. This neutralizing of the biasing current causes the center of modulation of the conductor 20 to take a position shown by the full lines of Fig. 4. Thus the center of modulations for high level sounds as shown at point H (Fig. 9) is shifted toward the center of the sound track 59.

The amount of biasing of the conductor is generally dependent upon the kind of sound being recorded. When recording dialogue or music in which the volume is low, or where the change in volume is gradual, the main biasing position of the conductor may be brought nearer to its closing position than in the case of recording staccato sounds such as are produced by a piano or harp. In recording the latter type of sound, more leeway has to be given to the conductor to prevent the high level wave forms from being clipped. This change in biasing position of the conductor is accomplished by means of variable resistance 63 (Fig. 6) and may be effected during recording whenever the tempo of the sound is changed. The change may be made between different types of recordings when the recorder is stopped or during operation of the recorder when the operator is aware of the nature of the sound to be recorded before impression thereof.

The amount of biasing is generally determined by the amount of margin between a depression of a wave form and the edge of the sound track as indicated at M (Fig. 8). Referring to Figs. 7 and 8, the margin may also be determined by the distance from the left hand edge 65 of the light slit 34 to the position of the conductor 20 at the upper limit of its excursions as indicated by the dotted line 66. In setting the biasing position of the conductor 20, the variable resistance 63 is manipulated until the distance X, representing one-half of the amplitude of the conductor excursions at an arbitrary low level single frequency 75

sound, is allowed to reach a certain percentage of the distance D (between the zero line of modulation in the biasing position and the edge of the sound track); this percentage, of course, depending on the type of sound being recorded. In recording soft sounds, the distance X may be allowed to cover as much as 85% of the distance D .

In the example shown in Fig. 8, the variable resistance 63 is set so that X will equal one-half D when the conductor is in its biased position. Thus, the margin for low level sounds is indicated by the dimension M . When the amplitude of the sounds is increased to a point at which X exceeds one-half D the change in biasing current causes the mean position of the conductor 20 to be moved downward so as to maintain approximately the same average ratio of X to D . This ratio will remain approximately constant until the conductor 20 reaches its unbiased position as shown by the dotted lines $20'$. In this position the ratio of M_1 to D_1 is still approximately equal to the ratio of M to D . As higher amplitudes are recorded, the zero line of modulation remains at C , provision being made in the rectifier R to prevent a shift of the zero line to the right of C , while the margin again becomes smaller as at M_1 to accommodate the higher amplitudes.

Referring to Fig. 9, the zero line of modulation is indicated by the center line 58 . Where no sound is recorded on the film only a narrow path of transparency 67 traverses the sound track. As modulations are recorded and increased, the zero line of modulation is moved outwardly toward the center of the sound track until the conductor reaches its unbiased position as indicated by the point H .

Due to the fact that the edges of the sound track are formed by the acute angle between the conductor 20 and the light slit 34 , these edges will not form sharp lines but will gradually pass from clear transparency to opacity as shown in Fig. 10. The amount of distortion, however, produced by this shaded zone 68 is negligible due to the fact that its dimension as measured transversely of the direction of the film travel remains constant and thus it is unable in itself to materially effect a varying change of light passing therethrough; it being understood, of course, that the reproduction of sound is dependent upon a change in the amount of light passing through the slit above the lowest audible frequency. The only possible effect of the shaded zone caused by frequency variations in the sound being recorded is to vary the direct current component, which does not change the frequencies making up the sound wave.

The biasing of the conductor 20 may also be accomplished by applying the rectified current from the rectifier 54 , which varies in accordance with the amplitude of the sounds being recorded, in a positive sense to the conductor 20 . In this case, the normal position of the conductor 20 would be mechanically adjusted so that at low level modulation it would be to the left of the center of the sound track or in a position shown by the full lines 20 of the conductor Fig. 7. With the increase in amplitude of the sound being recorded, the corresponding increase in rectified current from the rectifier 54 would shift the center of modulation of the conductor 20 to the position shown by the dotted lines $20'$. That is, instead of variably neutralizing a fixed electrical bias, the fixed electrical bias is eliminated and the rectified current variably biases the conductor in accordance with the average amplitude of the sound waves being recorded.

Having thus described the invention what is claimed as new and desired to secure by Letters Patent is:

1. A device for recording sound waves which comprises a system for transmitting light from a source to a photographic film, means for varying the amount of transmitted light comprising a member arranged in a magnetic field and having an elongated slit therein, a single electrical conductor arranged in the same magnetic field as said member and adjacent the slit in said member to define a light transmitting slot, means for supplying electrical current to said conductor to effect variation in the space relation between said conductor and said slit in accordance with the instantaneous values of said currents, and means for supplying a current to said conductor to effect a variation in the spaced relation of said conductor with respect to said slit in accordance with the envelope of said electrical currents, said conductor and said slit being disposed in oblique relation to each other.

2. In combination, a member located in a magnetic field and having a fixed elongated aperture therein, the same movable element suspended in a magnetic field and disposed in oblique relation to the aperture in said member, means to supply modulated electrical currents to said movable element to effect movement thereof in front of said aperture in said member in accordance with the instantaneous values of said currents, and means to supply current to said movable element to effect movement thereof in front of said aperture in said member in accordance with the envelope of said electrical currents.
